CORNICE CONSTRUCTION

Lionel Robbins, Larchmont, N. Y., assignor to Bartmann & Bixer, Inc., New York, N. Y., a corporation of New York

Application January 7, 1958, Serial No. 707,562

7 Claims. (Cl. 160—38)

This invention relates to cornice constructions—more particularly to an adjustable cornice structure with a replaceable fabric covering.

Conventional window cornices are commonly made of heavy wooden or slidably adjustable metal frames serving as a backing for permanently attached ornamental fabric coverings. Should it be desired to remove the coverings from such conventional frames, for cleaning or for replacement with other fabrics, considerable labor and skill is required not only in the work of removing the old coverings, but also in reattaching them by sewing, stapling or other conventional means. Moreover, when old coverings shrink in the washing process, it is often found that they cannot be replaced without considerable alterations.

It is the object of this invention to provide a light and inexpensive adjustable cornice having none of the shortcomings above mentioned—one with a covering that can be readily removed and adjustably replaced, and with a frame structure which can readily be mounted upon a curtain rod or similar support without any special skill and with a minimum of effort.

In the attainment of my objectives, I have conceived and produced a structure having a backing frame made of bendable, lightweight material, such as cardboard, adapted to receive thereover a fabric covering with rear marginal portions overlapping the top and bottom of the frame and extending therethrough, said overlapping portions being connected by yieldable connecting members which maintain the face of the covering in taut condition—the backing frame also being provided with differently positioned apertured portions carrying hooks adapted to be supported by a conventional curtain rod or other suitable horizontal support. In accordance with a further objective of my invention, the said yieldable members comprise, in a preferred construction, readily replaceable elastic bands attached to link members which are detachably secured to the said rear marginal portions of the fabric covering—said link and elastic members being positioned in a plane disposed forwardly of said hook members so as to be out of engagement with the said supporting rod. The arrangement is hence such that upon an operative detachment of the link and elastic members constituting the said connecting means the entire fabric covering can readily be removed; and upon the replacement of a new or shrunken covering, new elastic bands of suitable length can readily be substituted for the old bands, if deemed necessary. The construction is such that the said hook-carrying apertured portions are positioned at different horizontal levels, so as to enable the cornice to be set at a predetermined position with respect to the supporting rod, the frame being bendable in accordance with the proportions and configuration of said rod.

The specific details of an embodiment of my invention, as well as other objects, features and advantages thereof, will appear from the drawings and the description hereinafter given.

2

Referring to the drawings,

Figure 1 is a rear perspective view of a cornice construction in accordance with a preferred form of my invention, showing the fabric covering and hook members operatively in place.

Figure 2 is a front view of the structure of Figure 1, a portion of the fabric being removed for purposes of clarity.

Figure 3 is a rear view of the backing frame component of Figures 1 and 2 in unbent condition and without any attachments thereon.

Figure 4 is a fragmentary top view of the cornice construction of Figures 1 and 2 operatively in place over a supporting rod attached to a wall.

Figure 5 is a section of Figure 1 taken substantially along line 5—5, the dot-dash lines showing the relative position of a hook member, supporting rod and cornice when the latter is in an operatively raised position with respect to the rod.

Figure 6 is a section of Figure 1 taken substantially along line 6—6, the dot-dash lines showing the position of the supporting rod corresponding to the dot-dash position of the rod shown in Figure 5.

In the particular form of my invention illustrated, the backing frame 10, made of cardboard or similar lightweight bendable material, contains scorings 11 and 12 at the opposite lateral portions thereof, and a central scoring 13, the frame being bendable along any of said scorings. A fabric covering 14 is applied to the frame

10, the face 15 of the covering extending across the entire front surface 16 of the frame, said covering being folded back over the top and bottom edges of the frame and behind the rear surface 17 of the frame to form upper and lower rear marginal portions 18 and 19, respectively.

The said marginal portions 18 and 19 are connected by a plurality of spaced connecting members generally designated 20. In the particular embodiment illustrated, said connecting members are yieldable, and comprise upper and lower links 21 and 22, respectively, connected by an elastic band 23. Each link has a hooked end 24 and at the opposite end a ring portion 25, the terminal 26 of said ring portion being separated from the stem 27 of hook 24 to provide a space 28 through which the elastic band 23 can be passed for attachment to and removal from said links 21 and 22. In the preferred form illustrated, each of said links is of generally flat formation so that the hook 24, ring 25 and stem 27 are substantially in one plane. The vertical heights of the marginal portions 18 and 19 and the proportions of the links 21 and 22 and the elastic band 23 are such that the band is maintained in tension when the connecting members 20 are in their operative connecting positions illustrated in Figure 1, thereby keeping the covering 14 in predetermined assembled position on the frame 10, and the face 15 of the fabric in a taut condition.

The backing frame 10 contains a plurality of rows of holes or apertured portions A, B and C for operatively receiving therein and carrying the supporting hooks generally designated 29—the apertured portions of row A being generally designated 30, of row B 31 and of row C 32. The said hooks 29 are of generally conventional construction and have a front U-shaped branch 33 (see Figure 5) and a rear inverted U-shaped branch 34, the said U-shaped branch 33 being proportioned to extend through any one of said apertured portions 30, 31 or 32, and the inverted U-shaped branch 34 being adapted to extend over a supporting rod, such as a conventional curtain or drapery rod 35 attached to a wall 36 (Figures 4 and 5). A plurality of said hooks 29 are operatively inserted into the said apertured portions of any selected one of said rows A, B and C, depending upon the desired

relative position of the cornice with respect to the supporting rod 35. In the drawings said connections are shown inserted through holes 30 of row A to support the cornice at its lowest operative position with respect to supporting rod 35, Figure 5 showing by dot-dash lines one hook 29 inserted in a hole 31 of the intermediate row, whereby the cornice is obviously in a corresponding raised position with respect to the supporting rod 35.

It will be noted from Figure 6 that because of the generally flat configuration of link members 21 and 22, there is no interference whatsoever of the connecting members 20 with the supporting rod 35, regardless of the position of the cornice in relation to said supporting rod (see dot-dash position of rod 35). It will further be observed that the configuration of the hook 29 is such that the foremost terminal arm 33a of U-shaped portion 33 is flush against the front surface 16 of the frame 10, so that it will be entirely hidden by the fabric 14.

In attaching this device to the supporting rod 35 all that need be done is to determine the proportions of said rod, and then bend the frame 10 rearwardly along selected scoring lines 11 and 12 in accordance with such proportions, whereby the lateral inwardly bent sides 38 and 39 of the frame will be adjacent to the inwardly bent legs 40 and 41, respectively, of said rod 35. All that need be done thereafter is to operatively position the hooks 29 over adjacent portions of the rod 35, and the cornice will be in place.

If it is desired to remove the fabric covering 14 from the frame, the links 21 and 22 are operatively detached from the marginal portions 18 and 19, the detachment being accomplished simply by withdrawing the hooked terminals 24 from the fabric. If after such fabric has been washed it has shrunk, it may still be possible to employ the same elastic bands 23 in view of their yieldability. However, if it is necessary to employ new elastic bands, the old bands 23 can readily be removed through the said spaces 28 in the links 21 and 22, and replaced with new bands of proper length. If it is desired to employ a new fabric covering, it is not necessary that the vertical width of such fabric be identical with the old covering, since elastic bands 23 of proper length can readily be procured for use with such new covering.

It should be noted that the central scoring 13 enables the device to be folded along the middle, so that it may be conveniently packed for storage or shipping.

In the above description, the invention has been disclosed merely by way of example and in preferred manner; but obviously many variations and modifications may be made therein. It is to be understood, therefore, that the invention is not limited to any specific form or manner of practicing same, except insofar as such limitations are specified in the appended claims.

I claim:

1. In a cornice construction, a backing frame, a sheet of covering material having a front portion and upper and lower marginal portions, said front portion extending across the front face of said frame, said sheet being folded across the top and bottom edges of said frame whereby said marginal portions extend across correspondingly proportioned respective upper and lower marginal sections of the rear of said frame, a plurality of supporting hooks attached in spaced relation to said frame and extending rearwardly therefrom, and a plurality of spaced yieldable connecting members attached to opposed sections of said marginal portions, said hooks extending rearwardly beyond said connecting members.

2. In a cornice construction, a backing frame, a sheet of covering material having a front portion and upper and lower marginal portions, said front portion extending across the front face of said frame, said sheet being folded across the top and bottom edges of said frame whereby said marginal portions extend across correspondingly proportioned respective upper and lower marginal sections

of the rear of said frame, a plurality of supporting hooks attached in spaced relation to said frame and extending rearwardly therefrom, and a plurality of spaced yieldable connecting members each comprising upper and lower

links and an elastic element anchored to said links, each of said links being detachably secured to said respective upper and lower marginal portions of said sheet, said links and elastic element of each of said connecting members being substantially in one plane, said hooks extending

10 rearwardly beyond said plane.

3. In a cornice construction, a backing frame, a sheet of covering material having a front portion and upper and lower marginal portions, said front portion extending across the front face of said frame, said sheet being folded across the top and bottom edges of said frame whereby said marginal portions extend across correspondingly proportioned respective upper and lower marginal sections of the rear of said frame, said marginal portions being in spaced relation, thereby leaving a rear portion of said frame uncovered, said frame having extending therethrough in said uncovered portion thereof a plurality of apertured portions, a plurality of supporting hooks in supporting engagement with said apertured portions and extending rearwardly therefrom, and a plurality of spaced yieldable connecting members attached to opposed sections of said marginal portions, said hooks extending rearwardly beyond said connecting members.

4. In a cornice construction, a backing frame, a sheet of covering material having a front portion and upper and lower marginal portions, said front portion extending across the front face of said frame, said sheet being folded across the top and bottom edges of said frame whereby said marginal portions extend across correspondingly proportioned respective upper and lower marginal sections of the rear of said frame, said marginal portions being in spaced relation, thereby leaving a rear portion of said frame uncovered, said frame having extending therethrough in said uncovered portion thereof a row of apertured portions, a plurality of supporting hooks each having a rear substantially inverted U-shaped portion and a forward arm, said hooks being in supporting engagement with said apertured portions, each of said forward arms extending through one of said apertured portions and being in substantially flush engagement with the front face of said frame and behind said front portion of said sheet, each of said inverted U-shaped portions extending rearwardly from said frame, and a plurality of spaced yieldable connecting members attached to opposed sections of said marginal portions, said inverted U-shaped portions of the hooks extending rearwardly beyond said connecting means.

5. In a cornice construction, a backing frame made of thin bendable material, the opposite lateral ends thereof having a plurality of scorings transverse to the longitudinal extent of said frame, whereby the frame is bendable along selected ones of said scorings, a sheet of limp covering material having a front portion and upper and lower marginal portions, said front portion extending across the front face of said frame, said sheet being folded across the top and bottom edges of said frame whereby said marginal portions extend across correspondingly proportioned respective upper and lower marginal sections of the rear of said frame, said sheet being bendable together with said frame along selected ones of said scorings, a plurality of yieldable connecting members attached to opposed sections of said marginal portions, and a plurality of supporting hooks attached in spaced relation to said frame and extending rearwardly therefrom.

6. In a cornice construction, the combination according to claim 5, said frame having extending therethrough a plurality of rows of apertured portions, said hooks extending through and being operatively supported by the said apertured portions in one of said rows.

7. In a cornice construction, the combination accord-

ing to claim 5, said frame having extending therethrough a plurality of rows of apertured portions, said hooks extending through and being operatively supported by the said apertured portions in one of said rows, said connecting members each comprising upper and lower links and 5 an elastic loop removably anchored to said links, each of said links being detachably secured to said respective upper and lower marginal portions of said sheet.
